UNITED STATES PATENT OFFICE.

EMANUEL WILBURN WESTMORELAND, OF CHARLOTTE, NORTH CAROLINA.

ADVERTISING DEVICE.

Application filed October 13, 1925. Serial No. 62,287.

The object of my invention is to provide a novel rotary advertising device by means of which a series of advertising cards are successively displayed; and to provide novel means for continuously operating the device. I attain the objects of my invention by means of the apparatus illustrated in the accompanying drawings, in which:

Figure 1 is a front elevation of my invention, with part of the casing broken away;

Fig. 2 is a vertical section with the rotating display card wheel shown in side elevation;

Fig. 3 is an enlarged sectional view through one of the card holders; and

Fig. 4 is a similar view of a modified display card holder.

Like numerals indicate like parts in each of the several views.

Referring to the accompanying drawings, I provide a pair of standards 1 supporting the hub 3 of a revoluble double wheel 4 carrying oppositely disposed rods 5 from which are suspended the display card holders 7 by means of staples 6. A double oil cap 2 engages over hub 3, as shown in Fig. 2.

The card holders 7, as shown in Fig. 3, are provided with removable bottom strips 9 which support the advertising cards 8.

These display cards 8 may bear display advertising on both sides.

Instead of removable card 8 I may provide the permanent metal card 19 as shown in the form illustrated in Fig. 4 on which advertising may be painted or pasted.

Affixed to wheel 4 I provide a driven pulley 10 driven by belt 11 which in turn is driven by the belt pulley 12 of a suitable motor 13.

The entire device is enclosed in the housing 14 which is provided with opposite windows 15 provided with the panes 16. I provide suitable electric bulbs 17 and reflectors 18 for illuminating the display cards

as they are brought to display position in front of the glass panes 16. The device may be built any suitable size for carrying advertising cards varying from a few inches in width to a card of 5 ft. x 10 ft. As both sides of the advertising card carry an advertisement the device gives double advertising space. Each device is capable of carrying a large number of display cards owing to the size of the wheels 4.

It will require but little more space to install and operate one of these large devices

carrying many dozen advertisements than it will to work and operate a large billboard which, perhaps, would carry only one or two advertisements.

As the machine is operated by the motor the wheel 4 is kept revolving continuously and the advertisements are displayed in succession thus holding the attention of the reader. As opposite windows are provided in the housing the advertisements may be read from opposite sides of the device, thus utilizing both sides of the cards and giving a double display. The housing also prevents tampering with the motor which drives the apparatus as well as protecting it from the weather. If an electric motor is used it can be set to automatically cut off and on at predetermined hours. The card frames 7 swing freely on the transverse rods 5 and thus always remain in a vertical position.

For a large advertising device the sheet metal cards 19 are utilized on which large posters may be pasted or signs painted. The purpose of this sheet metal being to reduce the total weight of the device so that many cards may be used on one double wheel without having excessive weight.

The device also may be built to carry very small cards for use in show windows.

What I claim is:

1. An advertising device comprising a revoluble double wheel, standards for supporting the axle of the double wheel in an elevated position, horizontal rods mounted on the rims of the wheel in an equally spaced relation from each other, display card holders swingably suspended from the aforesaid rods, the width of the holders being less than the distance of the horizontal rods apart from each other to permit a free swinging movement of the holders, display cards bearing advertising on both sides thereof mounted in the aforesaid holders, a driven wheel affixed to the double card-holder carrying wheel, a source of power and means operatively connecting said driven wheel with the source of power.

2. In combination with the apparatus described in claim 1, a housing inclosing the aforesaid mechanism, said housing having opposite windows to permit of viewing the display cards from both sides of the housing.

3. In combination with the apparatus described in claim 1, a housing inclosing the aforesaid mechanism, said housing having opposite windows to permit of viewing the

display cards from both sides of the housing and means within the housing arranged above each of the opposite windows of the housing for illuminating the cards as they are moved into a position in front of the windows of the housing.

4. An advertising device comprising a revoluble double wheel, standards for supporting the axle of the double wheel in an elevated position, horizontal rods mounted in a spaced relation on the rims of the double

wheel said rods being positioned at a point on the rim midway between the spokes of the wheel, display card holders swingably suspended from the aforesaid rods, display cards bearing advertising on both sides thereof mounted in the aforesaid holders, the holders being swingable in vertical planes past each other, and power means for revolving the double wheel. ¹⁵
